United States Patent Office.

JACOB DOBBINS, OF LITCHFIELD, MICHIGAN.

Letters Patent No. 95,207, dated September 28, 1869.

IMPROVEMENT IN LATH-MACHINE.

The Schedule referred to in these Letters Patent and making part of the same.

To whom it may concern:

Be it known that I, JACOB DOBBINS, of Litchfield, in the county of Hillsdale, and State of Michigan, have invented a new and useful Improvement in Lath-Cutting Machines; and I do declare that the following is a true and accurate description thereof, reference being had to the accompanying drawings, and to the letters of reference marked thereon, and being a part of this specification, in which—

Figure 1 is a front elevation of my device;

Figure 2 is a front elevation of the equalizing feed-gear at the rear end of the machine;

Figure 3 is a plan view of the finishing-cutters; and

Figure 4 is a similar view of the first cutters.

Like letters refer to like parts in each figure.

The nature of this invention relates to an improved machine for cutting laths from bolts of wood; and consists in the arrangement of a series of feed-rollers for forcing the bolt in contact with two pairs of stationary knives, each pair of which cuts a lath from the bolt in its passage through the machine; also, in the peculiar arrangement of its parts, as hereinafter more fully shown and set forth.

In the drawings—

A represents a proper frame, surmounted in front by a feed-table, B.

C is a driving-shaft, journaled in proper bearings at the front and rear ends of the machine frame.

D is a spur-gear, secured to the driving-shaft, outside of the rear bearings, and engages with the larger spur-wheels E and E' on the roll-shafts F and F', journaled at each side and below it, in the cross-beam of the frame at the rear end of the machine.

The shafts F and F' project forward into the frame of the feed-table, and are provided with the corrugated rollers G and G', for forming the under feed, the roller G being provided with a collar or flange, H, which guides the inner edge of the bolt in its passage, and, being set inward from the inner knife, the thickness of the inner lath by it is gauged to the cut of said knife.

I and I' are the shafts carrying the upper feed-rollers J and J', and which are journaled at their rear end to the cross-beam of the frame, where they receive motion by their spur-gears, K and K', meshing with similar gears, L and L', on the shafts F and F'.

Said gears L and L' being of the same diameter as the gears K and K', all of their shafts and rollers revolve at the same speed.

The driving-shaft C is extended over the feed-table, and has secured to its end the spiked drum M, which, with its shaft, revolves at a higher speed than do the shafts of the feed-rollers, for the reason which I shall presently explain.

The front bearings of the upper roller shafts are in an elastic semi-elliptic yoke, N, secured to the machine

frame behind the feed-table, so that in case a bolt of greater than the usual thickness be fed to the rollers, they will rise up and ease the bolt in its passage without choking the rollers, as would be the case were they journaled in a rigid frame.

O and O' are angular knives, securely bolted to the frame, between the feed-rollers, and are set forward from the guiding-gauge H the thickness of a lath, and inclined on their cutting-edges, so as to give a drawing cut on the bolt.

The lower knife O' first cuts the lath one-half through the bolt, while the upper and rear knife O completes the division.

P and P' are knives, similarly arranged, but so secured to the frame that they will cut a second lath from the bolt in its passage through the machine.

The spiked drum M, revolving with greater speed than the train of feed-rollers, tends to assist them in carrying the bolt along by the spikes on its periphery cutting into the surface of the bolt. It also serves as a carrier in returning the bolt after the laths have been cut from it, as I will presently explain.

Q are ordinary carrying-rollers, journaled into the feed-table, the discharge-end of which is inclined, as shown.

R and R' are spiked drums, revolving in proper bearings at the top and bottom of the inclined apron of the feed-table, and are rotated by belt r from a pulley on the shaft C, to the pulley r' of the drum R, and from which pulley a second belt, r'', transmits the motion to the pulley r''' on the drum R'.

When the bolt has had the laths cut from it, and reaches the spiked drums R and R', and rests on their upper surfaces, it will be moved back by them toward the knives, when the operator directs its right end over the spiked drum M, which delivers it at the proper point to be again fed to the knives, to guide the bolt to its proper position in re-entering the feed-rollers.

A rotating rest, S, is pivoted to the back-frame of the feed-table, so that when the bolt drops on it, it will be guided directly to its place, when it will be automatically sent forward by the vibrating lever T, pivoted at its lower end to the legs of the frame, and weighted on its inner side to keep it toward the feed-rollers.

When the bolt is brought back from the drum M, its right end is brought to the shoulder t, at the top of the vibrating lever T, which is carried back until the other end of the bolt has passed the centre of the rotating rest and dropped on the feed-table, when the weight U on the lever will move the bolt along to the rollers, or materially assist the operator in so doing.

To cause the bolt to be automatically carried to the feed-rollers, the carrying-roller Q, under the rotating rest S, may be rotated by a crossed belt from a pulley

on the feeding-shaft C, if desired, in which case its shaft should project far enough behind the frame of the feed-table to receive a pulley for that purpose.

This device is equally adapted to cutting lath with saws. In this case the knives are dispensed with, and one or more saws are attached to an additional shaft under the drive-shaft C, and propelled by it by means of a belt and pulleys.

What I claim as my invention, and desire to secure by Letters Patent, is—

The rotating rest S, and in combination therewith, the vibrating lever T, constructed and operating as and for the purpose aforesaid.
